UNITED STATES PATENT OFFICE.

CARL AUGUST AMBROSIUS, OF EAST ORANGE, NEW JERSEY, ASSIGNOR OF ONE-HALF TO CHARLES H. SHANGER AND JESSE E. SHANGER.

ADJUSTABLE FORM FOR STAIR-BUILDERS.

SPECIFICATION forming part of Letters Patent No. 699,057, dated April 29, 1902.

Application filed December 2, 1901. Serial No. 84,363. (No model.)

To all whom it may concern:

Be it known that I, CARL AUGUST AMBROSIUS, a citizen of the United States, residing at East Orange, in the county of Essex and State of New Jersey, have invented certain new and useful Improvements in Adjustable Forms for Stair-Builders and other Woodworkers; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The objects of this invention are to facilitate the work of bending wood to a desired form, more particularly in connection with stair-building, making arches for windows and doorways, and for bending wood for any other purpose; to enable with one appliance or apparatus various and different forms to be obtained over which the wood may be bent; to facilitate the work of changing the form over which the wood is bent from one shape to another, and to secure other advantages and results, some of which may be referred to hereinafter in connection with the description of the working parts.

The invention consists in the improved adjustable form for carpenters and builders, and particularly for stair-builders, and in the arrangements and combinations of parts of the same, all substantially as will be hereinafter set forth and finally embraced in the clauses of the claim.

Referring to the accompanying drawings, in which like letters of reference indicate corresponding parts in each of the several figures, Figure 1 is a plan of my improved device. Fig. 2 is a detail section of the same, taken at line *x*. Fig. 3 is a detail section taken through line *y*; and Fig. 4 is a similar section, on an enlarged scale, showing a variation in detail construction. Fig. 5 is a plan showing a construction sometimes preferred, in which the device is provided with attachments by which the forms may be increased in variety; and Fig. 6 is a side view of the construction shown in Fig. 5. Fig. 7 is a detail section taken at line *y'* of Fig. 5.

In said drawings, *a* indicates the body or frame of my improved form, of which *b b b*

are radiating arms connected integrally by segments *c c*, the said radiating arms extending from the center of said frame or body with which the said segments are concentric to points outside of or beyond the convex sides of said segments. The said arms at their extremities are preferably provided with clamping means, whereby the wood to be bent may be held against the form, as hereinafter described.

The segments *c c* are provided with curved slots *d*, and the arms *b* are longitudinally slotted, as at *e*. The said slots *d* and *e* have adjustable posts *f* therein, which are adapted to be set within said slots by nuts *g* or by any other suitable means, and the said posts *f* extend laterally or vertically from the segments *c* and arms *b* and at or near their projecting extremities are threaded to receive screws *h*. Said posts are preferably in sections, of which the section *f'* of each is adapted to be rigidly clamped to the frame or body *a* by the said nut *g* and provides a box or pivotal bearing for the section *f''*, having the threaded seat *f'''* for its screw *h*, thus permitting a free and easy turning or automatic adjustment of said section *f''* and its screw. Said screws *h* are each provided at one end with a head *i*, Figs. 3 and 4, which is arranged in a swiveled socket *j*, as indicated in Figs. 3, 4, and 5. The said sockets in turn are pivoted, as at *k*, upon eyes *l*. The said eyes are arranged at uniform distances along one side of a flexible form *m*, the said flexible form being preferably of sheet or strap-like steel. I prefer to employ in connection with said form a greater number of eyes than screws, whereby the said screws to meet certain conditions can be pivoted upon one or another of said eyes to secure the desired shapes.

The flexible form *m* is adapted to be bent into a semicircle, as in Fig. 1, or it may have an ogee curve, as in Fig. 5, or the curvatures and shapes may be varied indefinitely to suit conditions required by the work, the form being changed by turning the screws *h* within their respective posts or studs *f* either from or toward the center of the frame or otherwise, and the shapes being, furthermore, changed by sliding the posts within their respective slots and then clamping said posts in said slots.

The flexible form *m* having been given the

desired shape, the wood in the form of veneer, thin boards, or strips is covered with glue at the outer side and is then bent over the outer side of the form or the side opposite the side having eyes *l*. A second strip of wood is then applied to the first, the second strip having received a proper application of glue, and the said boards or strips thus bent and laid against one another are clamped against the said flexible form by means of the clamps applied to or arranged in connection with the arms *b*, although I may employ in some cases independent clamps such as are commonly found in a carpenter's or stair builder's shop. The clamps preferred, however, consist each of a sliding clamp-jaw *n*, carried by an arm *o*, arranged on a screw *p*, having a crank *r*, by which it may be conveniently turned. The cranks *r* are arranged in ears or bearings *t*, formed at or near the extremities of the arms *b*, so that by turning the crank *r* the screw carries the sliding clamp-jaw thereon from or against the outer side of the glued wood, in the latter case pressing the strips together against the form *m*, as will be understood.

After the two strips have been glued and clamped and the glue having dried a third strip may be similarly attached to the first two, and this may be repeated as often as necessary to secure the desired thickness of bent wood.

After making the several applications of layers of wood and the drying of the glue the bent wood may be removed from the device, when it will be found to retain the desired shape.

When I desire to secure the ogee curve of Fig. 5, I employ in connection with the frame *a* a slotted and curved arm *t'*, Figs. 5 and 6, which is braced to the central arm of the frame by means of a pivotal brace *u* and is pivotally connected at *z* to a segment of the frame. The brace *u* is adjustable in relation to the said central arm by means of a series of perforations *v* and a pin *w*. The said arm *t'* is provided with posts *f*, in which the screws *h* are arranged, and is swiveled upon a swivel-socket attached to the inner side of the flexible form.

To hold the central part of the flexible form *m* down upon the frame *a*, the central arm of the frame is preferably slotted, as at *b'*, Figs. 6 and 7, the slot being similar to a dovetailed slot, and the said form *m* contiguous to the said slot *b'* is provided with a headed arm or extension *b²*, the head of which lies in the larger interior portion of the slot, thereby holding the said flexible form down firmly upon or close to the frame. In connection with the contiguous or adjacent screw *e* the said arm *b²* gives firmness to the said form upon the frame.

Having thus described the invention, what I claim as new is—

1. The combination with the frame *a*, hav-

ing longitudinally-slotted radiating arms provided with posts adjustable in the slots thereof, of screws arranged in said posts, and a flexible form loosely connected to said screws, the said form being adapted to be changed in shape when the said screws are turned, substantially as set forth.

2. The combination with a frame having segments with curved slots, of a flexible form over which wood may be bent, screws connected to said form and arranged in adjustable bearings, said bearings being arranged in said curved slots and the said form being adapted to be changed in shape by the turning of said screws, substantially as set forth.

3. The combination with a frame having arms integrally connected by a segmental part, said frame being slotted in said segment and arms, adjustable posts or studs arranged in said slots, screws arranged in said posts or studs and having heads arranged in pivoted swivel connections, eyes for the pivoted swivel connections, arranged on a flexible form and said flexible form, substantially as set forth.

4. The improved form for stair-builders, comprising a frame having radiating arms *b*, *b*, *b*, each of which is longitudinally slotted and certain of which are each at its end provided with a bearing for a clamp-screw *p*, said arms being connected by slotted segments *c*, *c*, adjusting-screws *h*, arranged on adjustable studs or posts in the slots of the arms and segments, said studs having means for holding the same in said slots, connections for connecting the said adjusting-screws to the flexible form, and said flexible form, substantially as set forth.

5. The combination with the frame and flexible form of an arm *t'*, carrying adjusting-screws loosely attached to said form and a brace connecting the frame and arm to hold the latter in place, substantially as set forth.

6. The combination with the frame and flexible form connected to said frame at one end of a slotted arm *t'*, and adjusting-screws connected to said form and arranged in studs adjustably fastened in the slot of said arm, and a brace *u*, for holding said arm in fixed relation to said frame, substantially as set forth.

7. The combination with the frame and flexible form connected at one end to said frame, of an arm *t'*, pivoted at one end upon said frame and held rigidly thereto by a brace said arm being provided with adjusting-screws connected to said form, substantially as set forth.

In testimony that I claim the foregoing I have hereunto set my hand this 15th day of November, 1901.

CARL AUGUST AMBROSIUS.
